INSERT FOR GOLF CLUBS

Filed August 3, 1923

George W. Mattern
by Dr. P. Walker
Attorney

UNITED STATES PATENT OFFICE.

GEORGE W. MATTERN, OF DAYTON, OHIO, ASSIGNOR TO THE CRAWFORD, McGREGOR AND CANBY COMPANY, OF DAYTON, OHIO, A CORPORATION OF OHIO.

INSERT FOR GOLF CLUBS.

Application filed August 3, 1923. Serial No. 655,437.

My invention relates to golf clubs and more particularly to the method of securing inserts in the heads of golf clubs.

It is customary to balance the club head and improve the efficiency by inlaying the head of golf club to secure the proper degree of impact upon the ball when struck to insure long distance flight and low trajectory. Ordinarily the striking face of a golf club is inlaid with a body of ivory or some ivory substitute. One of the present materials being a casein product of ivory like density and hardness. While ivory or the materials having the characteristics of ivory are preferred other materials also are widely used for such insert structure. Club heads are also frequently provided with metal weights usually located at the rear of the club or substantially in alinement with the point of impact. More or less difficulty has been experienced in keeping such inserts and weights tightly seated in the club head. The club head of wood and the insert in some instances are quite susceptible to atmospheric and climatic changes permitting shrinkage and consequent loosening of the insert.

The present invention contemplates a method of securing inserts in the striking face of golf club heads as well as the securing of the weight body at the rear of the club by positive means which will obviate the difficulties due to expansion and contraction under varying conditions. In the present instance the main insert body in the striking face is secured by screw threaded studs positioned coincident with the margin of the insert whereby the threaded portions of the studs intersect the inserted body and simultaneously intersect and engage in the main body of the club head. These anchor studs may be of material having characteristics similar to the insert but if desired of different color whereby the insert face will present an ornamental and pleasing design. In the event that the club is provided with a weight or other insert at its rear side the striking face insert may be provided with an extended shank screw threaded into the rear weight body.

The object of the invention is to simplify the manner of applying and securing insert

bodies in the heads of golf clubs whereby such clubs may not only be cheapened in construction, but will be more efficient in playing more durable and unlikely to get out of repair.

A further object of the invention is to provide improved means for positively connecting the insert body with the main body of the club head whereby it may not be loosened and displaced by relative shrinkage of the parts.

A further object of the invention is to provide improved means for securing insert bodies in the club heads whereby the head will be reinforced and strengthened to prevent splitting or cracking of the head.

A further object of the invention is to interconnect the weight body and the impact member of the striking face whereby the full effect and momentum of the weight may be transmitted directly to the ball at the moment of impact.

A further object of the invention is to provide locking means for the insert which will afford a pleasing and ornamental design for the striking face.

With the above primary and other incidental objects in view as will more fully appear in the specification, the invention consists of the features of construction, the parts and combinations thereof, and the mode of operation, or their equivalents, as hereinafter described and set forth in the claims.

Referring to the drawings Fig. 1 is a perspective view of a golf club head in which the present invention has been embodied. Fig. 2 is a transverse sectional view through a golf club head provided with an impact insert in the striking face and a weight body at the rear of the head said bodies being positively interconnected one with the other. Fig. 3 is a similar transverse sectional view illustrating the anchorage of an inserted impact body without the addition of the connected weight. Fig. 4 is a perspective view illustrating the possibility for variation of the striking face design by employment of the present method of anchoring the inserts. Figs. 5 and 6 are sectional view and face view respectively illustrating a further modification and vari-

ation of design affected by arrangement of the insert.

Like parts are indicated by similar characters of reference throughout the several views.

In the drawings 1 indicates a wooden golf club head having in the striking face 2 thereof an inserted impact body 3. The insert body 3 may be of any suitable material 10 but is usually made of ivory or some ivory substitute. The body 3 is substantially cylindrical in form and conforms to and accurately fits the socket or receiving recess in the body 1. Ordinarily such inserts are 15 cemented and reliance placed wholly upon the cement to hold the insert against displacement. In the present instance there are provided a plurality of screw threaded anchor studs 4. These anchor studs 4 are 20 preferably though not necessarily of the same material as the main insert body 3 but may be differently colored to afford a pleasing design. The anchor studs 4 are located substantially coincident with the marginal 25 outline of the body 3 in such relation that they simultaneously intersect with the inserted body 3 and also the main body 1 of the club head. These anchor studs are located by drilling and threading the stud 30 holes subsequent to the insertion of the main body 3. The threaded engagement of the anchor studs 4 on one side with the insert body 3 and on their opposite sides with the main body 1 of the golf club head holds the 35 insert in fixed position in relation with the club head and prevents its displacement. Preferably the threaded holes to receive the anchor studs 4 do not extend to the full depth of the insert body 3 thereby leaving 40 an unintersected portion 5 having a shoulder beyond the inner extremity of the threaded stud. In Fig. 2 there is shown the usual metal weight 6 located at the rear of the head 1. Such weight bodies are usually attached to the club head by screws passing 45 forwardly through the metal weight and into the main body 1 of the club head. The heads of such attachment screws or the filling inserted in the screw holes over the head 50 of such screws mars the appearance of the external face of the weight body 6. In the present case the weight body 6 is connected directly to the impact body 3 by means of an integral shank 7 on one of these bodies which 55 is screw threaded into the other. In Fig. 2 the shank is shown formed integral with the insert 3 and having a screw threaded end 8 engaged with the weight 6. This shank 60 7 not only serves to attach the weight body 6 and hold it tightly in place but it also assists in anchoring the insert 3 in the driving face and preventing it becoming loosened in its seat. Moreover the shoulder 9 formed 65 at the juncture of the shank 7 with the body 3 acting in opposition to the weight body 6

drawn inward by the threaded engagement 8 of the shank 7 affords a clamping effect which reinforces and strengthens the wooden head 1 to prevent splitting. Moreover the weight body 6 being directly connected with 70 the body 3 by the interconnecting shank 7 the momentum of the weight and its effect upon the swing of the club is transmitted directly to the impact body 3 and to the ball at the moment of the impact therewith. The 75 direct connection of the impact body 3 with the follower weight 6 thus obviates any vibration or lost motion in the body 1 of the club head and insures the full effect of the follower weight 6 being transmitted directly 80 to the ball. While this is the preferred construction it is not necessary that the insert body 3 be connected to the weight body 6 in order to secure it in its position and this is illustrated in Fig. 3 wherein the insert body 3 is not connected rearwardly with the weight.

By employing the threaded anchor studs 4 insert bodies of various shapes may be fixedly secured in the striking face. In Fig. 90 4 there is shown a variation wherein a rectangular insert is anchored by a threaded stud 4 at each corner. While affording all the advantages of secure anchorage in positive connection of the insert the present construction permits a wide variation of design 95 which affords a variety of striking faces of pleasing appearance.

Figs. 5 and 6 illustrate further possibilities of the present construction to afford 100 clubs of characteristically different appearance. In this construction the main insert body 3 is provided with a central anchor stud 10 extending entirely through the insert body 3 and engaging in the head of the club but not extending into engagement 105 with the weight 6 as in Fig. 2. This anchor stud 10 is provided with an enlarged head 11 having a shouldered piece within the insert 3. Located at opposite sides of the centrally disposed anchor stud 10 and simultaneously engaging not only the head 1 and primary insert 3 but also the head of the anchor stud 10 are additional anchor studs 12. These studs 12 like the studs 4 do not extend 110 to the full depth of the primary insert 3 but have shouldered engagement at their inner ends with such insert and also threaded engagement on one side with the club head 1 and on the opposite side with the head 11 or the central studs 10 and further threaded engagement intermediate these points with the primary insert 3. By making the several members 3, 11 and 12 of different colored material striking faces of 115 characteristically different appearance may be afforded.

From the above description it will be apparent that there is thus provided a device 120 of the character described possessing the 125

particular features of advantage before enumerated as desirable, but which obviously is susceptible of modifications in its form proportions, detail construction and arrangement of parts without departing from the principle involved or sacrificing any of its advantages.

While in order to comply with the statute the invention has been described in language 10 more or less specific as to structural features, it is to be understood that the invention is not limited to the specific details shown, but that the means and construction herein disclosed comprises the preferred form of several modes of putting the invention into effect and the invention is, therefore, claimed in any of its forms or modifications within the legitimate and valid scope of the appended claims.

20 Having thus described my invention, I claim:

1. In a golf club the combination with a club head of an impact body embedded in the striking face of the head and a plurality of 25 screw threaded anchor studs, also located in the striking face of the club head, substantially upon the marginal line of the insert body with one side of their screw threaded portions intersecting and engaging in the impact body and the other side of such screw threaded portions intersecting and engaging in the main portion of the club head.

2. In a golf club the combination with a 35 golf club head, of a circular impact body embedded in the striking face thereof, and a plurality of studs also embedded in the striking face of the club head and having anchoring engagement simultaneously with the circular impact body and with the main portion 40 of the head of the club.

3. In a golf club the combination with a club head, of an insert body embedded in the striking face of the head, and a plurality of 45 screw threaded studs also embedded in the striking face of the club head and substantially coincident with the margin of said insert body and having simultaneous engagement with the insert and with the club head, said insert body and studs being of differently colored materials to afford distinctive 50 color designs.

4. In a golf club, the combination with a club head of a face plate embedded in the striking face of the club, an insert body embedded in the striking face of the club head within the boundary of the face plate and a plurality of studs also embedded in the striking face of the club head and indenting the marginal line of the insert body, said face 55 plate, insert body and studs being of differentially colored material, to form in association with each other distinctive color designs.

5. In a golf club, the combination with a 65 club head of a plurality of differently

colored inserts embedded in the striking face of the golf club head to form in association with each other distinctive color designs.

6. In a golf club the combination with the golf club head of a revolvable impact 70 body embedded in the striking face of the club head, a non-revolvable weight body embedded in the rear face of the club head, and an intermediate connection between the impact body and the weight body.

7. In a golf club, the combination with the club head of an insert body revolvably mounted in the striking face of the club head, and, a screw threaded shank upon the revolvable insert body, and a non-revolvable 80 weight body embedded at the rear side of the club head with which the screw threaded shank engages.

8. In a golf club, the combination with a club head of an insert body mounted in 85 the striking face of the club head, and a weight body embedded in the rear portion of the club head, and a revolvable screw threaded coupling member interconnecting the impact body and weight body.

9. In a golf club, the combination with a club head of an insert body revolvably mounted in the striking face of the club head, and a weight body embedded in the rear portion of the club head, and a screw 95 threaded shank upon one of said embedded bodies and engaging the other embedded body.

10. In a golf club, the combination with a club head of an impact body embedded in 100 the striking face of the club head and a non-revolvable weight body embedded in the rear face of the club head, and revolvable coupling means for relatively adjusting the embedded impact and weight bodies in relation with each other.

11. In a golf club, the combination with the club head of a revolvable impact body embedded in the striking face of the club head, a weight body embedded in the rear 110 face of the club head said bodies being relatively adjustable by the rotation of the impact body, and means for locking the impact body against rotation.

12. In a golf club, the combination with a golf club head of a revolvable impact body embedded in the striking face of the club head means for securing the impact body therein by the rotation thereof, and anchor studs screw threaded into the striking face 120 of the club in positions intersecting the impact body and also intersecting the main body of the club head adjacent to such impact body.

13. A game club having an insert in its striking face, which comprises a central insert and a plurality of smaller inserts in grooves in said central insert, and means on the surface of said smaller inserts for retaining them in position.

14. A game club having an insert in its striking face, which comprises a central insert and a plurality of lateral inserts of the same material as the central insert, angularly disposed and having their contiguous faces shaped to cooperate throughout a substantial portion of their length.
15. A game club having an insert in its striking face, which comprises a central insert and a plurality of smaller inserts, said smaller inserts being provided with retaining means and being arranged to interlock with said central insert.
16. A game club having a wooden head provided with a resilient insert in the striking face thereof, which comprises a larger insert, a smaller insert passing through at least a portion of the larger insert and into the wood of said head, and interlocking means on said smaller insert for retaining it and the larger insert in position.
17. In a golf club, the combination with a club head, a revolvable insert body embedded in the striking face of the club head within the boundary of the face and a plurality of studs also embedded in the striking face of the club head and indenting the marginal line of the insert body.

In testimony whereof, I have hereunto set my hand this 23rd day of July, A. D. 1923.

GEORGE W. MATTERN.
